WIRE FENCE

William H. Sommer, Peoria, Ill., assignor to Key-
stone Steel & Wire Company, Peoria (South
Bartonville), Ill., a corporation of Illinois

Application July 29, 1938, Serial No. 221,937

7 Claims. (Cl. 245—8)

This invention has reference to improvements in wire fencing and particularly to that type which is factory made and intended for farm, field and kindred uses. Furthermore, the fence 5 comprises top and bottom marginal or selvage wires, a plurality of intermediate line wires, and stay wires, each comprising a single piece of wire connected with the opposite marginal or selvage wires and with each of the intermediate wires. 10 The invention has for its primary object to produce a wire fence in which, by employing gauges of wire comparable to that in like height and spacing of fence, less wire will be used and yet the fence so produced will be as strong, if not stronger, as fences now or heretofore made. 15 In accomplishing the economical use of wire, while retaining strength in the fence, I provide continuous one piece stay wires, the upper and lower terminal ends of which are preferably 20 coiled or looped once around the marginal or selvage wires, the latter being provided with crimps, at spaced intervals for seating the coiled or looped ends of the stay wires, such crimps in the opposite marginal or selvage wires being disposed oppositely to and directed towards each other and the body of the fence whereby a saving 25 in the stay wires is made to the extent of the depth of the crimps in said marginal or selvage wires. Such crimps are individual crimps to receive an end of a single stay wire and they diverge 30 outwardly from adjacent the stay wire on opposite sides thereof, where they form a seat, to the body of the marginal wire into which such divergent portions merge. The bodies of the stay 35 wires where they intersect the intermediate line wires, being twisted and combined therewith in off-set tension curves thereby obviating the use of and saving the wire required to produce the tension curve heretofore formed in the respective 40 intermediate line wires, between the stays.

It is a further object of the invention to flatten the inner faces of the apex portion of the crimps in the marginal or selvage wires, at the point where the terminal ends of the stay wires engage 45 the same, so as to prevent the marginal wires leaving their position or turning on their axis.

The invention further contemplates, in one form, the crimping of the bodies of the stay wires adjacent their coiled or looped ends at the marginal wires, so that the bodies of the stay wires are substantially in the same plane as the marginal and intermediate wires and the coiling of the free ends of the stay wires about their bodies at the juncture of the crimps, thus effecting a 50 strong and secure connection and increasing the

load required to pull the stay wires off the marginal or selvage wires.

It is further contemplated, in the connection of the terminal ends of the stay wires with the marginal or selvage wires in another form, to weld such free ends of the stay wires to their own bodies. The purpose in each instance, aside from giving strength to the fence, is to avoid and obviate any free or loose ends in the stay wires where the fencing is used in territories where wool is produced. Welding lends itself to fences made from low carbon wire and when high carbon wire is used then the other means of attachment may be used, although this is optional with the maker. 10

That the invention may be more fully understood reference is had to the accompanying drawings, illustrating preferred embodiments of the invention, in which—

Fig. 1 shows a section or panel of my improved fence where the free ends of the stay wires are 20 coiled about their bodies;

Fig. 2 is a view similar to Fig. 1 except that the free ends of the stay wires are welded to their bodies;

Figs. 3 and 4 are enlarged spot views of the 25 upper and lower ends of a stay wire and its connection with the marginal or selvage wires and with its own body, at points 3—3 and 4—4 respectively, Fig. 1;

Figs. 5 and 6 are end views of Figs. 3 and 4 30 respectively;

Fig. 7 is an enlarged spot view of an off-set tension curve at the point where a stay wire and an intermediate line wire are twisted together;

Fig. 8 is an enlarged spot view of an end of a 35 stay wire and its connection with a marginal or selvage wire and its own body as the same would appear at points 8—8 Fig. 2;

Fig. 9 is an end view of Fig. 8, and

Fig. 10 is an enlarged detail view, in section, 40 showing the flat face of a crimp in a marginal or selvage wire and how the looped or coiled portion of the end of a stay wire is interlocked therewith when bent over or about such marginal or selvage wire.

Like characters of reference denote corresponding parts throughout the figures.

The fence, whether of the character shown in Fig. 1 or Fig. 2 comprises top and bottom marginal or selvage wires 10 and 11 respectively, and a 50 plurality of intermediate line wires 12. The number of the intermediate wires 12 employed will depend on what height fence is desired. The stay wires are designated 13, and they may be spaced apart six, nine or twelve inches as demand may 55

necessitate, or whatever spacing may be desired.

The marginal wires 10, both at the top and the bottom of the fence, where the terminal ends of the stay wires are connected therewith or thereto, 5 are crimped, as at 14. The crimps in the top marginal or selvage wire are directed downwardly and toward the body of the fence and the crimps in the bottom marginal or selvage wire are directed upwardly and toward the body of the 10 fence, and the inner face of the apex or seat portion of each crimp is flattened, as at 15, see Figs. 5, 6 and 10. Such crimps are individual crimps to receive an end of a single stay wire and they diverge outwardly from adjacent the stay wire 15 on opposite sides thereof, where they form a seat, to the body of the marginal wire into which such divergent portions merge.

Each stay wire 13 where it intersects an intermediate line wire 12 is twisted therewith in a 20 tension curve, as at 16 and their opposite or upper and lower ends are coiled or looped once about a marginal wire, as at 17, and such coiled or looped ends are seated in the flattened portion of the crimps 14, see Fig. 10, and when so seated slight 25 indentations 15a are formed in the stay wire to produce an interlocking effect between the stay wire and the marginal or selvage wire. The crimps in the marginal or selvage wires, constructed as they are with seats and diverging out- 30 ward portions act to prevent the individual single stay wires from slipping sidewise on the marginal or selvage wires and the flattened faces of the crimps in which the coiled terminal ends of the stay wires are seated, together with the in- 35 terlocking connection between the coiled ends of the stay wires and such seats, so formed, prevent the marginal wires from leaving their position or turning on their axis.

In Fig. 1 the free ends of the stay wires are 40 coiled or looped around their bodies, as at 18, see also Figs. 5 and 6, and in Fig. 2 I have shown the free terminal ends of the stay wires welded to their bodies, as at 19, see also Figs. 8 and 9. The latter connection is adaptable for use when 45 reasonably low carbon wire is used and the former connection is adaptable for use when high carbon wire is used.

The stay wires, in the form shown in Figs. 1, 3, 4, 5 and 6, immediately adjacent their coiled 50 or looped ends around the marginal or selvage wires are preferably crimped or formed with reverse bends 20, whereby the bodies of the stay wires, between the marginal or selvage wires, are substantially in the same plane therewith. Also, 55 in this form, the ends of the stay wires are coiled tightly about their bodies and at the juncture of the crimps or reverse bends 20, in their bodies, which lends additional securement of the stay wires and increases the load required to pull the 60 stay wires off the marginal or selvage wires.

What I claim is:

1. A wire fence comprising marginal wires, intermediate line wires and spaced separate and individual continuous one piece stay wires connecting the opposite marginal wires and each of the intermediate line wires, each marginal wire having correspondingly spaced crimps directed toward the opposite marginal wire and body of the fence and arranged to receive and seat the 65 terminal end of an individual stay wire, and each stay wire having its terminal ends looped around a marginal wire and seated within a crimped portion and its ends connected with the body of the stay wire, such crimps having portions diverging from its seat and extending outwardly from

adjacent a stay wire and merging into the marginal wire to confine the stay wire from sidewise movement along the marginal wire, and the body portions of each stay wire where they intersect an intermediate line wire being twisted therewith in an off-set tension curve. 5

2. A wire fence comprising marginal wires, intermediate line wires and continuous one piece stay wires connecting the marginal wires and each of the intermediate line wires, each marginal wire 10 having correspondingly spaced crimps directed toward the opposite marginal wire and body of the fence and having the inner faces of the apex portion of such crimps flattened, and each stay wire having its ends looped around a marginal wire and seated within a crimped portion and its ends connected with the body of the stay wire, and the looped portion of the stay wire being indented where it engages the flattened faces of said crimped portions to provide an interlocking 20 relation between such stay wires and said marginal wires, and the body portions of each stay wire where they intersect an intermediate line wire being twisted therewith in an off-set tension curve. 25

3. A wire fence comprising marginal wires, intermediate line wires and spaced separate and individual continuous one piece stay wires connecting the opposite marginal wires and each of the intermediate line wires, each marginal wire 30 having correspondingly spaced crimps directed toward the opposite marginal wire and body of the fence and arranged to receive and seat the terminal end of an individual stay wire, and each stay wire having its terminal ends looped once around a marginal wire and seated within a crimped portion, such crimps having portions diverging from its seat and extending outwardly from adjacent a stay wire and merging into the marginal wire to confine the stay wire from sidewise movement along the marginal wire, said stay 40 wires having their body portions adjacent the marginal wires crimped so that the bodies of the stay wires are in the same plane as the marginal and line wires and having the free ends of the stay wires coiled about their bodies at the juncture of the crimp, and the body portions of each stay wire where they intersect an intermediate line wire being twisted therewith in an off-set tension curve. 45

4. A wire fence comprising marginal wires, intermediate line wires and continuous one piece stay wires connecting the marginal wires and each of the intermediate line wires, each marginal wire 55 having correspondingly spaced crimps directed toward the opposite marginal wire and body of the fence and having the inner faces of the apex portion of such crimps flattened, and each stay wire having its ends looped once around a marginal wire and seated within a crimped portion and being indented at such flattened faces to provide an interlocking relation between said looped portions and such crimps, said stay wires having their body portions adjacent the marginal wires crimped so that the bodies of the stay wires are in the same plane as the marginal and line wires and having the free ends of the stay wires coiled about their bodies at the juncture of the crimp, and the body portions of each stay wire where they intersect an intermediate line wire 60 being twisted therewith in an off-set tension curve. 65

5. A wire fence comprising marginal wires, intermediate line wires and spaced separate and individual continuous one piece stay wires con- 75

- necting the opposite marginal wires and each of the intermediate line wires, each marginal wire having correspondingly spaced crimps directed toward the opposite marginal wire and body of the fence and arranged to receive and seat the terminal end of an individual stay wire, and each stay wire having its terminal ends looped once around a marginal wire and seated within a crimped portion and the free ends of the stay wires welded to their bodies immediately adjacent the marginal wires, such crimps having portions diverging from its seat and extending outwardly from adjacent a stay wire and merging into the marginal wire to confine the stay wire from sidewise movement along the marginal wire, and the body portion of each stay wire where they intersect an intermediate line wire being twisted therewith in an off-set tension curve.
6. A wire fence comprising line wires and stay wires, one or more of such lines wires formed
- 5 with crimps, one face of which is flattened, and the stay wires being looped about the line wires and having portions seated within such crimps and indented so as to provide an interlocking connection between such line wires and stay wires.
7. In a wire fence, the combination of a strand wire and a stay wire, the former having a crimp providing a seat for the terminal end of the stay wire, the latter having its terminal end looped 10 over the strand wire and seated in said crimp and the free end of the terminal portion of the stay wire welded to its own body in adjacency to the strand wire, said crimp in the strand wire having portions diverging from its seat and extending 15 outwardly from adjacent the stay wire and merging into the strand wire to confine the stay wire from sidewise movement along the strand wire.
